UNITED STATES PATENT OFFICE.

LUIGI MOMBARUZZO, OF NEW YORK, N. Y., ASSIGNOR OF ONE-THIRD TO PHILIP BENVISSUTO AND ONE-THIRD TO OLINDO O. CECCARINI, BOTH OF NEW YORK, N. Y.

REDUCING VALVE.

Application filed April 12, 1921. Serial No. 460,723.

To all whom it may concern:

Be it known that I, LUIGI MOMBARUZZO, a citizen of Italy, residing in New York city, county of New York, borough of Manhattan, 5 and State of New York, have invented certain new and useful Improvements in Reducing Valves, of which the following is a full, clear, and exact specification.

My invention relates to reducing valves 10 and refers particularly to reducing valves operative by temperature means.

While the device of my invention is broad in its scope of application, I refer to its particular use with gas burners simply as a 15 means of illustration and without any limitation to that particular use.

Grave danger is always incident to the use of gas for illuminating and heating purpose, in that the accidental, or deliberate, 20 extinguishment of the flame without the closing of the pipe valve allows a full head of gas to escape from the burner, frequently resulting in the loss of life.

The same result is obtained, if the pipe 25 valve is accidentally, or deliberately, opened without ignition of the escaping gas.

The device of my invention overcomes these and many other serious and objectionable results incident to the use of the usually 30 employed valve.

In the employment of the reducing valve of my invention, the extinguishment of the flame automatically reduces the flow of gas to a non-dangerous and unobjectionable 35 degree, allowing a flow sufficient only for purposes of slight ignition when desired.

Further, in the employment of the reducing valve of my invention, the opening of the usual valve without ignition does not 40 allow the full flow of gas but maintains it in the non-dangerous and unobjectionable degree above mentioned.

Further, the employment of the reducing valve of my invention does not interfere 45 with the usual illuminating, or heating, properties of the burner, because the ignition of the gas escaping through its reduced area automatically opens the reducing valve to its fullest extent, thus allowing the full flow 50 of gas.

It is evident, therefore, that the employment of my reducing valve allows a reduction in the amount of gas flow due to temperature control and, in the specifically de-

scribed example of its application, a reduction of temperature reduces the gas flow.

In the accompanying drawings, illustrating modified forms of the device of my invention, similar parts are designated by similar numerals.

Figure 1 is a vertical plan view, partly in cross-section, of one form of my device as used with a gas burner.

Figure 2 is a section through the line 2—2 of Figure 1.

Figure 3 is a broken vertical cross-section of a modified form of the device of my invention.

Figure 4 is a bottom view of the closure means of Figure 3.

The particular form of a device of my invention applied to a gas light equipment, as shown in the accompanying drawings, comprises a gas pipe 10, carrying the key valve 11 and the burner 12 in which is inserted an ordinary gas tip 13. Fixedly attached to the inner face of the wall of the gas tip 13 is a transverse partition 14, having the larger aperture 15 and the smaller aperture 16. Supported by the partition 14 is a thermostat 17, the other end of the thermostat 17 having fixedly attached a wire 18 extending through the aperture 15 and carrying the ball 19.

Figures 1 and 2 show the device in operation with the gas ignited. The gas under these conditions flows freely through the apertures 15 and 16 and the heat produced by the flame 20 is transmitted to the burner 12 and the thermostat 17 retains the aperture 15 in an open position, as shown. Should the flame 20 be extinguished, the burner 12 will cool and the thermostat 17 will raise the ball 19, closing the aperture 15 and preventing the flow of gas therethrough. The only gas that can then escape through the tip 13 is that passing through the aperture 16, which is so small in amount as not to be dangerous, or objectionable, and this can, of course, be entirely eliminated by closing the key valve 11.

In order to light the gas, the key valve 11 is opened and the gas passing through the aperture 16 is lighted at the tip 13 and, within a few seconds, the heat thus produced causes the thermostat 17 to open the aperture 15 by lowering the ball 15, thus giving the full illuminating efficiency.

It will thus be seen that the only gas that can escape, when it is not ignited, is that passing through the small aperture 16, even if the key valve 11 is accidentally left open 5 and that the ignition of this small amount of gas will automatically open the larger aperture 15.

In the modified form of my device, shown 10 in Figures 3 and 4, the partition 14 has but one opening 21 which is capable of being thermostatically closed by the member 22, which has a small recess 23 through which a 15 small amount of gas can escape, similarly as through the aperture 16 in the device of Figures 1 and 2.

The thermostat may be of any shape and material, or materials, which will thermostatically reduce the gas passage area, and it may be attached to any suitable portion 20 of the device.

It is also evident that the apertures may be of various sizes and in various positions within the device for reducing the gas passage area.

25 I do not limit myself to the particular size, shape, number, material or arrangement of parts as shown and described, all of which may be varied without going beyond the scope of my invention as shown, described 30 and claimed.

What I claim is:—

1. In a gas burner, in combination, a chamber, a transverse horizontal partition within the chamber having an opening there-

in, a U-shaped thermostat entirely within the 35 upper chamber fixedly attached at one end, a wire carried by the free end of the thermostat and extending through the partition opening, a valve member carried by the wire within the lower chamber and pendant from 40 the thermostat and capable of free vertical movement, to open and close the partition opening, the thermostat allowing the valve member to be free from the opening at normal temperatures and carrying the valve 45 member vertically upwardly closing the opening at temperatures above the normal.

2. In a gas burner, in combination, a chamber, a transverse horizontal partition within the chamber having a larger opening 50 and a smaller opening therein, a U-shaped thermostat entirely within the upper chamber fixedly attached at one end, a wire carried by the free end of the thermostat and extending through the larger partition opening, a ball carried by the wire within the lower chamber and pendant from the thermostat capable of free vertical movement 55 to open and close the larger partition opening, the thermostat allowing the ball to be 60 free from the opening at normal temperatures and carrying the ball vertically upwardly closing the opening at temperatures above the normal.

Signed at New York city in the county of 65 New York and State of New York this 11th day of April, 1921.

LUIGI MOMBARUZZO.
